DESIGN FOR A SPOOL COVER FOR TYPE-WRITING MACHINES

Clarence H. Bills, New York, N. Y., assignor to Royal Typewriter Company, Inc., New York,
N. Y., a corporation of New York

Application April 28, 1934, Serial No. 51,570

Term of patent 14 years

To all whom it may concern:

Be it known that I, CLARENCE H. BILLS, a citizen of the United States, residing at New York, in the county of New York and State of New York, have invented a new, original, and ornamental Design for a Spool Cover for Typewriting Machines, of which the following is a specification, reference being had to the accompanying drawing forming part thereof.

In the accompanying drawing, the figure is a perspective view of a spool cover for typewriting machines showing my design.

I claim:

The ornamental design for a spool cover for typewriting machines substantially as shown.

In testimony whereof, I have hereunto subscribed my name.

CLARENCE H. BILLS.
